United States Patent Office.

LOUIS BLACK, OF DETROIT, MICHIGAN.

Letters Patent No. 95,872, dated October 19, 1869.

IMPROVEMENT IN SPRING EYE-GLASSES.

The Schedule referred to in these Letters Patent and making part of the same.

To all whom it may concern :

Be it known that I, LOUIS BLACK, of Detroit, in the county of Wayne, and State of Michigan, have invented a new and useful Improvement in Spring Eye-Glasses; and I do hereby declare that the following is a full, clear, and exact description thereof, which will enable others skilled in the art to make and use the same, reference being had to the accompanying drawing.

This invention relates to improvements in connecting the springs to the eye-glass, having for its object to provide more durable connections of the springs to the said frames, and which connections may be readily detached.

The invention consists in connecting the said springs to the said projections, by means of clamps, either provided with eccentric clamping-pawl, or provided with rivets, arranged to be tightened by wedging against wedge-shaped projections, widest at the outer ends, toward which the clamps, when connected around the narrower parts, are drawn, the ends of the springs in all cases being placed between the projections and the clamps, and provided with locking-devices, to prevent sliding out between the clamps and projections, all as hereinafter more fully specified.

Figure 1 represents a side view of a pair of spring-glasses, connected according to my improvement;

Figure 2 represents a longitudinal section through one of the said connections;

Figure 3 represents a similar section through the other connection;

Figure 4 represents a section of another arrangement of the said connection; and

Figures 5 and 6 represent two different arrangements for the ends of the springs, to prevent them from sliding out of the clamps.

These springs are commonly connected to the eye-glass bows by rivets, which weaken both the springs and the parts of the bows or frames through which the rivet-holes are made, and they are difficult to remove when required, which is frequently the case.

These objections I propose to obviate by clamping the springs to the said projections of the eye-glass bows, and this I propose to do by various arrangements of the clamping-devices, in respect of the details.

At A, figs. 1 and 2, I make a clamp, *a*, which I pivot to the projection of the eye-glass frame at *b*, so as to oscillate to some extent, and having room between the top of the projection *c* and the wall of the top of the clamp, for the ready insertion of the end of the spring; also, having an eccentric pawl, *d*,

at the upper lower corner, arranged to work against the end of the projection, which is curved for the reception of the pawl.

The said pawl, when turned down into the position represented at A, figs. 1 and 2, clamps the spring and projection rigidly together.

The end of the spring may be bent down slightly, with a corresponding recess at the base of the projection *e*, as represented at *c*, as a further security against being drawn out.

At *f*, fig. 6, I have shown an extension of the end of the spring, so as to form a hook for engaging more permanently with the projection *O*, which is designed to be correspondingly recessed for the reception of the same, and at *g*, fig. 5, I have shown a projection rising from the upper side of the spring, to engage behind the clamp, and formed by punching or indenting the spring from the under side.

I propose to make use of any equivalent means for preventing the withdrawal of these springs.

At *B*, fig. 2, I have shown a clamp, *b'*, not pivoted to the projection *e*, but arranged to slip over the outer end of the said projection, which is thicker at the said end, and to be secured by a rivet or pin, *d'*, put in after the clamp is slipped on, and passing under the said projection.

This clamp is tightened up by drawing it back toward the end of the projection, after the spring has been put in place, and the bent end engaged with the recess at the bottom of the projection. This arrangement is clearly shown in section at fig. 3.

The modification shown at fig. 4 differs from the arrangement at A, figs. 1 and 2, only in the respect that the projection *c* is considerably shortened, and the eccentric pawl *d* works down upon the spring.

The pawl *d* need not necessarily have an extension or handle, but will work equally well if made as an eccentric rivet, except that it may not be turned as readily.

Having thus described my invention,

What I claim as new, and desire to secure by Letters Patent, is—

1. Connecting the springs of spring eye-glasses to the eye-glass frame by clamps *a* *b'*, when arranged to be secured by wedge-formed devices, or their equivalents, substantially as specified.

2. In combination with the said clamps, the bent projections at the ends of the springs, or their equivalents, substantially as specified.

LOUIS BLACK.
